UNITED STATES PATENT OFFICE.

JOHN F. LEEPER, OF ALTON, ILLINOIS.

CORN-HARVESTER.

No. 812,215.

Specification of Letters Patent.

Patented Feb. 18, 1906.

Application filed May 29, 1905. Serial No. 262,784.

To all whom it may concern:

Be it known that I, JOHN F. LEEPER, a citizen of the United States, residing at Alton, in the county of Madison and State of Illinois, 5 have invented certain new and useful Improvements in Corn-Harvesters, of which the following is a full, clear, and exact description, reference being had to the accompanying drawings, forming a part hereof.

10 My invention has relation to improvements in corn-harvesters; and it consists in the novel construction and arrangement of parts more fully set forth in the specification and pointed out in the claims.

15 In the drawings, Figure 1 is a top plan view of the machine with parts broken away. Fig. 2 is a vertical longitudinal section on line 2 2 of Fig. 1. Fig. 3 is a front elevation thereof, and Fig. 4 is a side elevation of the 20 rear end of the machine.

The present invention is an improvement on the construction of corn-harvester shown and described in United States Letters Patent issued to me under date of November 17, 25 1903, No. 744,571, and has for its object to simplify the construction by which the removal of the cornstalks is effected by the driving-gear of the machine, the dumping cradle of the patented device being herein 30 omitted.

A further object is to provide suitable means for guiding and feeding the cornstalks to the cutters so as to insure uniformity in results.

35 A further object is to improve the machine in minor details, the advantages of which will be better apparent from a detailed description of the invention, which is as follows:

40 Referring to the drawings, A represents a platform mounted on runners B, adapted to be drawn between two adjacent rows of corn. Disposed along one side of the harvester and inclined to the longitudinal axis thereof is a 45 member 1, which at the forward end is supported by a post 2, secured to the laterally-projecting stationary blade 3, carried by the platform, the rear end of the member 1 being supported by a bracket 4, secured to one of the runners B. Disposed across the harvester and secured at one end to the member 1 are a series of transverse members 5, curving toward the opposite side of the machine, their opposite ends being secured to the ad-

jacent runner B, Fig. 3. These members 5 55 are arranged in pairs and serve to support the perforated plates 6, which collectively constitute or form the depositing-surface for the cut corn. The lower curved ends of the members 5 encompass the longitudinally-disposed rock- 60 shaft 7, the forward end of the latter being supported in the boss or bearing 8, formed in the shield 9, carried by the platform immediately rearward of the driver's seat S, the rear end of said rock-shaft 7 being supported in a 65 bracket 10, secured to the runner B on that side of the machine. It may be stated in passing that the rear edge of the rear plate 6 is supported on a flat transverse member 5', whose end loosely embraces the shaft 7, and 70 it may be further remarked that the members 5 may be of any cross-section, the angle-iron form being specially desirable to support the plates 6. The bracket 10 connects with the terminal transverse member 5" of the ma- 75 chine.

The forward end of the rock-shaft is provided with a crank-arm 11, normally held depressed by a spring 12, coupled at one end thereto and at its opposite end to a pin 13 80 on the runner B. Pivotedly coupled to the arm 11 is a link 14, whose upper end is loosely connected to the end of the adjacent arm of a tripping-lever 15, pivoted in a bearing 16 on the platform, the opposite arm of 85 the lever being provided with a foot-rest or pedal 17 for the driver. The end of the short arm of the lever 15 is coupled to a link 18, which is pivotally connected to a clutch-lever 19, pivoted to the lug 20 on top of the plat- 90 form, the lever 19 extending a suitable distance beneath the platform, Fig. 2. The lower end of the lever 19 controls the movable clutch member 21, which latter (upon proper oscillation of the lever 19) co-operates 95 with the stationary clutch member 21', forming the hub portion of the sprocket-wheel 22, mounted at the rear end of the longitudinal shaft 23. The forward end of the shaft 23 carries a bevel-pinion 24, which meshes with a bevel-gear 25, formed with the wheel W at one end of the axle 26. The opposite wheel W has a similar bevel-gear 25', meshing with a pinion 24' at one end of a parallel shaft 23', the rear end of the latter carrying the crank- 100 arm 27, which actuates the connecting-rod 28, directly connected to the reciprocating knife-blade 29. This latter feature is, however,

similar to my patented device, and I make no claim thereto in the present application.

Leading from the sprocket-wheel 22 is a chain 30, which passes under the member 1, 5 over a sprocket-wheel 31 on an exterior longitudinal shaft 32, mounted in brackets 33, carried by the runner B. This shaft 32 is provided with sprocket-wheels 34 35, from which lead chains (or belts) 36 37, the latter 10 being disposed on either side of one of the plates 6 and in the space between two adjacent plates 6, the opposite ends of the chains passing over sprocket-wheels 38 39, whose hubs are loosely mounted on the rock-shaft 7, 15 about which they are free to rotate. The chains are provided with arms 40, which, as subsequently to be explained, advance the corn deposited on the depositing-surface and dump the same off from the side of the machine. The rock-shaft 7 is provided with arms 20 41 to temporarily support the cornstalks on the machine before they are dumped.

Rotatable with the wheel W and located on the side opposite to the gear-wheel 25 is 25 a bevel-gear 42, which engages a pinion 43, whose shaft is mounted at one end of an inclined bracket 44, cast with the standards 45 46. The pinion-shaft is provided with a sprocket-wheel 47, from which passes a chain 30 (or belt) 48 over a sprocket-wheel 49 at the upper end of the bracket 44. This chain 48 is provided with a series of feed-arms 50, which as the chain travels feed the cornstalks to the cutters, the parts revolving, as shown 35 by the arrows in the drawings. The gathering-hooks 51 52 are the same as in my patent above referred to.

The operation of the harvester may be described as follows: As the machine advances 40 along the ground the knife 29 will be reciprocated, as already indicated, and the cornstalks thus cut will fall over on the depositing surface or plates 6. The rotation of the wheels W serves to rotate the bevel-gear 42; 45 which from the connections described imparts the necessary travel to the feed-chain 48, the arms 50 of the latter feeding the cornstalks positively to the cutters. When the operator desires to dump the contents of the 50 machine from the lower side of the depositing-surface, he places his foot on the pedal 17, this action depressing the short arm of the lever 15 and raising the long arm. The elevation of the long arm exerts a pull on the 55 link 14, Fig. 3, thereby oscillating the arm 11 against the tension of the spring 12 and rocking the rock-shaft 7 in a direction to depress the arms 41. (See dotted position in Fig. 3.) The depression of the short arm of the lever 60 15 serves to pull on the link 18, thus tilting the clutch-lever 19 in a direction to force the clutch members 21 21' together. This action (it being remembered that the shaft 23 rotates with the advance of the machine over

the field) at once sets into motion the chain 65 30, which in turn rotates the shaft 32. The latter imparts motion to the chains 36 37, whose arms 40 shove the cornstalks along the plates 6 until they are dumped from the side of the machine over the now depressed arms 70 41, which latter have been swung out of the way of the advancing contents previously deposited on the plates 6. When the contents has been dumped, the operator simply removes his foot from the pedal, the spring 12 75 restoring the parts to their first position.

I may of course depart in a measure from the details here shown without in any wise affecting the nature or spirit of my invention.

Having described my invention, what I 80 claim is—

1. In a harvester, a suitable platform, adapted to be advanced over the field, a depositing-surface for the cut material, a rock-shaft having a series of arms for retaining the 85 material on the surface on which it has been deposited, a series of belts disposed in proximity to the depositing-surface, arms carried by the belts and projecting beyond the surface, suitable running-wheels for the machine, and intermediate gearing under the control of the operator for periodically setting the belts into motion and rocking the shaft to a releasing position for the arms carried thereby, substantially as set forth. 95

2. In a harvester, a suitable platform, a depositing-surface at the receiving side thereof inclining downward toward the discharging side, a longitudinally-disposed rock-shaft at the discharging side of the machine, a rotatable shaft parallel to the rock-shaft at the opposite side of the machine, a series of transverse belt conveyers disposed between the shafts, arms formed on the conveyers and projecting beyond the depositing-surface, 100 running-wheels for the machine, an operating-lever under the control of the operator, and intermediate connections to simultaneously impart motion to the belt conveyers and rock the rock-shaft to a releasing position, the parts operating substantially as, 110 and for the purpose set forth.

3. In a harvester, a suitable platform, a series of cutters, a permanently-advancing feed belt or chain for the stalks fed to the cutters, 115 a transversely-disposed belt conveyer, means for setting the same intermittently into action for removing the contents from the side of the machine, substantially as set forth.

4. In a harvester, a depositing-surface for 120 the cut material, a platform, running-wheels therefor, bevel-gears on said wheels, pinions meshing with the gears, parallel shafts leading from the pinions, suitable cutters, intermediate connections between the latter and 125 one of the shafts, a controlling-lever, a clutch member on one of the parallel shafts controlled by the depression of the controlling-

lever, a belt conveyer for removing the contents deposited on the machine, intermediate connections between the conveyer and the clutch member for imparting motion to the conveyer upon depression of the controlling-lever, devices for temporarily retaining the material in position on the machine and means coupled to the controlling-lever for shifting the retaining devices and thereby

releasing the contents upon the removal thereof by the conveyer, substantially as set forth.

In testimony whereof I affix my signature in presence of two witnesses.

JOHN F. LEEPER.
